UNITED STATES PATENT OFFICE.

ALBERT E. PFAU, OF ROCKFORD, ILLINOIS.

VENDING-MACHINE.

1,397,604.

Specification of Letters Patent.

Patented Nov. 22, 1921.

Application filed September 30, 1918. Serial No. 256,336.

To all whom it may concern:

Be it known that I, ALBERT E. PFAU, a citizen of the United States, residing at Rockford, in the county of Winnebago and 5 State of Illinois, have invented certain new and useful Improvements in Vending-Machines, of which the following is a specification.

This invention relates to vending machines, and more particularly to liquid spraying machines.

The object of the invention is to provide a simply constructed and efficient machine of this character whereby the insertion of a 15 coin or check will release the actuating mechanism therefor.

Another object is to provide simple and efficient means to prevent the actuation of the discharge or ejecting mechanism until 20 released by the coin.

Another object is to provide novel means for ejecting and spraying a liquid from the apparatus.

Another object is to provide improved 25 means for ejecting the coin after it has actuated the mechanism.

With the foregoing and other objects in view, which will appear as the description proceeds, the invention resides in the combination and arrangement of parts and in the 30 details of construction hereinafter described and claimed, it being understood that changes in the precise embodiment of the invention herein disclosed may be made 35 within the scope of what is claimed without departing from the spirit of the invention.

In the accompanying drawings:—

Figure 1 represents a side elevation partly 40 in section of the apparatus constituting this invention, the casing in which it is inclosed being shown in section,

Fig. 2 is a horizontal section through the casing with the mechanism shown in plan 45 view,

Fig. 3 is a transverse vertical section taken on the line 3—3 of Fig. 1,

Fig. 4 is a detail fragmentary longitudinal section taken on the line 4—4 of Fig. 2, 50 and

Fig. 5 is a detail fragmentary transverse sectional view thereof.

In the embodiment illustrated, the apparatus constituting this invention is inclosed 55 within a casing 1 divided by a vertical parti-

tion 2 into two compartments 3 and 4. Secured to the bottom of the compartment 3 is a cup-shaped member 5 having a flange 5' extending therefrom and secured to said bottom. This cup-shaped member 5 is designed to retain and support a vessel 6 in the form of a bottle which may contain perfume or any other liquid to be vended. A pipe 7 extends into said bottle and is provided at its upper end with a nozzle 8 which projects laterally from the front wall of the casing 1, said front wall 3' being composed of glass or other transparent material so that the label contained on the bottle may be readily seen from outside the casing so that the purchaser may know just what kind of perfume he is going to obtain.

A tube or pipe 9 leads from the nozzle stopper of the bottle and has a bulb 10 at its rear end, the pipe extending through the 75 vertical partition 2 so that the pipe is positioned in compartment 4 near the top thereof (see Fig. 1). This bulb 10 is covered by a hood 11 against which the upper portion of the bulb is designed to bear, the inner 80 face of the hood being made to conform to the shape of the bulb as is shown clearly in Fig. 1.

This hood 11 is supported by uprights 12 rising from the horizontal partition 13 85 spaced from the bottom of the compartment 4 and which is designed to support the mechanism which actuates the apparatus as will be hereinafter more fully described. Below this partition 13 is arranged a coin receiving drawer 50, and mounted on the partition are the uprights 12 above described. These uprights 12 are slotted longitudinally at their upper ends as shown at 15 and a rod 16 is designed to reciprocate in the slots. 95 Blocks 17 are carried by this rod and operate as guides, being shaped to fit within the slots 15.

Carried by the rod 16 is a convex block 18 positioned below the bulb 10 and which 100 is designed to be forcibly engaged with the bulb when the block is raised for the purpose presently to be described. Bars 19 are connected at one end with the rod 16 on opposite sides of the block 18 and at their 105 other end are connected with crank arms 20 which project laterally from a shaft 21. This shaft 21 is shown angular in cross section with rounded portions at its ends to form journals mounted to turn in bearings 110

carried by the upper ends of standards 22 secured to the partition 13 as is shown clearly in Fig. 3.

An arm 23 is fixed to the shaft 21 at one end thereof and has a right angularly extending handle 24 projecting through the adjacent side wall of the casing 1 as is shown clearly in Figs. 2 and 3, said casing being slotted to permit the handle to turn therein.

10 Two rack bars 25 spaced laterally apart are mounted to reciprocate horizontally in guides 26 secured to the upper face of the partition 13. Coiled springs 27 are attached at one end to the guides 26 and at their 15 other ends to lugs 28 which depend from the rack bars 25 and said springs exert their tension to retract the rack bars and to return them to normal position after they have been reciprocated.

20 Fixed to the shaft 21 are two gears 28' mounted to mesh with the rack bars 25 so that when the shaft is turned the rack bars will be reciprocated against the tension of their springs 27 and this turning of the shaft 25 by means of the handle 24 not only reciprocates the rack bars but operates to lift the crank arms 20 and to raise the bars 19 connected therewith so that the block 18 is forcibly engaged with the bulb 10 and thus operates to eject the liquid from the nozzle 8 in a manner well known in atomizers.

A ratchet bar 29 is carried by one of the rack bars 25 and is designed to engage a depending arm 30 when the rack bar is secured 35 against the tension of its spring.

A standard 31 rises from the partition 13 between the guides 26 which carry the rack bars and the standard supports at its upper end a track 32 on which is mounted to reciprocate a coin carrying platform 33. This 40 platform 33 is carried by an upright 34 fixed at its lower end to the inner end of the rack bar opposed to that which carries the ratchet bar 29, said standard 34 being offset inwardly to position the platform between the track 32 above referred to.

The arm 30 which projects in the path of the ratchet bar 29 is made in the form of a pawl and is carried by a bar 36 pivoted at its rear end at 37 to a bracket 37' projecting inwardly from the rear wall of casing 1. This 50 bar 36 is spanned by a guide 38 which is shown inverted U-shaped in form and operates to prevent lateral movement of the bar 36 as well as to limit its upward movement. The front end of this bar 36 is rounded as shown at 36' and extends over the coin receiving platform 33 so that when said platform carries a coin and moves rearwardly under said bar 36, the coin will operate to 55 lift the bar and thus move the arm 30 out of the path of the ratchet bar 29 permitting the rack bars to move rearwardly a sufficient distance to elevate the block 18 so as to cause 60 it to forcibly engage the bulb 10 and eject 65

the desired amount of liquid from the bottle 6.

The track 32 is provided with longitudinally spaced depending kickers 32' which are positioned in the path of the coin platform and constructed to permit the coin to pass freely thereunder when the platform moves rearwardly and to drop down over the coin when the platform is so positioned and to engage the coin and force it off the platform when it moves forwardly.

A coin chute 39 extends from one wall of the casing 1 and discharges directly over the platform 33 and is provided at its outer end with a lip 40 to receive and direct the 80 coin into the chute.

In the operation of the apparatus, a coin inserted through chute 39 will drop down onto the platform 33 and the apparatus is then ready for ejecting the liquid which is accomplished by the turning of shaft 21 through the handle 24 and arms 23 which causes the gears carried by said shaft to rotate and through their intermeshing engagement with the rack bars 25 to reciprocate 90 said bars rearwardly. This rearward movement of the rack bars causes the platform carrying standard 34 to move rearwardly carrying with it the coin which has been inserted through the chute 39. This movement of the coin elevates the track 32 carrying with it the arms 30 so that said arms are moved out of the path of the ratchet bar 29 thus unlocking the bulb compressing mechanism so that the further turning of the 100 gears will operate to raise the block 18 through the arms 19 and 20 and compress the bulb 10 causing the atomizer with which it is connected to operate and spray the liquid from the bottle onto the person or 105 an object held by him in front of the atomizer.

After the rack bars have moved rearwardly a predetermined distance against the tension of their springs 27 the coin riding 110 under the kickers 32' during this movement, and when pressure on the handle 24 is relieved the rack bars will move forwardly under the action of their springs 27 and cause the coin carried by the platform to be 115 engaged by the kickers 32' and knocked off said platform. The coin so discharged will drop into the drawer 50 which is suitably located and access thereto can only be obtained by an authorized person.

From the above description it will thus be seen that the apparatus can only be operated by the insertion of a suitable coin in the chute 39 to unlock the bulb compressing device. This coin is preferably a penny, but 125 any other suitable coin may be used according to the amount of liquid to be ejected by the bulb.

From the foregoing description, taken in connection with the accompanying drawings, 130

the advantages of the construction and of the method of operation will be readily apparent to those skilled in the art to which the invention appertains and while I have

5 described the principle of operation of the invention together with the device which I now consider to be the best embodiment thereof, I desire to have it understood that the device shown is merely illustrative and
10 that such changes may be made as are within the scope of the claimed invention.

Having thus fully described my invention, what I claim as new and desire to secure by Letters Patent, is:—

15 1. A perfume vending machine including a container equipped with compressible means for dispensing the contents thereof, a rotatable shaft carrying mechanism to operate the compressing means, gear wheels carried by said shaft, and spring retained 20 rack bars in mesh with said gear wheels and operable by movement of said shaft to tension the springs of the rack bars whereby the latter are automatically retracted when
25 the shaft is released.

2. In a machine of the class described, an inclosing casing, a liquid container therein having a nozzle with a bulb connected therewith, reciprocatory means for compressing said bulb to eject the liquid from said container, a rotary shaft, crank arms connecting said shaft with said reciprocatory means, a gear fixed to said shaft, a reciprocatory rack meshing with said gear, coöperating means carried by said rack and casing for locking the shaft against turning, and coin controlled means for releasing said locking means.

3. In a machine of the class described, an 40 inclosing casing, a liquid container therein having a nozzle with a bulb connected therewith, reciprocatory means for compressing said bulb to eject the liquid from said container, a rotary shaft, crank arms connecting said shaft with said reciprocatory means, a gear fixed to said shaft, a reciprocatory rack meshing with said gear, coöperating means carried by said rack and casing for locking the shaft against turning, means for releas-

ing said locking means, and means for removing said releasing means after the compression of the bulb.

4. In a machine of the class described, an inclosing casing, a liquid container therein having a nozzle with a bulb connected therewith, reciprocatory means for compressing said bulb to eject the liquid from said container, a rotary shaft, crank arms connecting said shaft with said reciprocatory means, a gear fixed to said shaft, a reciprocatory rack meshing with said gear, coöperating means carried by said rack and casing for locking the shaft against turning, means for releasing said locking means, and kickers for removing said releasing means after the compression of the bulb.

5. In a machine of the class described, an inclosing casing, a liquid container therein having a nozzle with a bulb connected therewith, reciprocatory means for compressing said bulb to eject the liquid from said container, a rotary shaft, crank arms connecting said shaft with said reciprocatory means, a gear fixed to said shaft, a spring retracted reciprocatory rack meshing with said gear, coöperating means carried by said rack and casing for locking the shaft against turning, and coin controlled means for releasing said locking means.

6. In a machine of the class described, an 80 inclosing casing, a liquid container therein having a nozzle with a bulb connected therewith, reciprocatory means for compressing said bulb to eject the liquid from said container, a rotary shaft, crank arms connecting said shaft with said reciprocatory means, a gear fixed to said shaft, a reciprocatory rack meshing with said gear, a ratchet bar carried by said rack, a pawl carried by said casing in the path of said ratchet bar for locking the gear against turning, and liftable means connected with said pawl.

In testimony whereof I affix my signature in presence of two witnesses.

ALBERT E. PFAU.
